Primary Examiner — John Windmuller*Assistant Examiner* — Steven Czyz(74) *Attorney, Agent, or Firm* — Senniger Powers LLP(57) **CLAIM**

The ornamental design for a dispenser for dispensing cleaning solutions, as shown and described.

DESCRIPTION

FIG. 1 is a perspective view of a dispenser for dispensing cleaning solutions of the present invention;

FIG. 2 is a front view of the dispenser of FIG. 1, the rear view forming no part of the invention;

FIG. 3 is a right side elevation of the dispenser of FIG. 1, the left side elevation being a mirror image thereof;

FIG. 4 is a top plan of the dispenser of FIG. 1; and,

FIG. 5 is a bottom plan of the dispenser of FIG. 1.

The broken lines depict portions of the article that form no part of the claimed design.
